CLAIM

The ornamental design for a tape dispenser, as shown and described.

DESCRIPTION

FIG. 1 is a right side elevational view of a tape dispenser showing our new design, with the left side elevational view being a mirror image;

FIG. 2 is a front elevational view;

FIG. 3 is a rear elevational view;

FIG. 4 is a top plan view;

FIG. 5 is a bottom plan view; and,

FIG. 6 is a top perspective view thereof, the roll of tape depicted by means of broken lines being shown for illustrative purposes only and forming no part of the claimed design.
